UNITED STATES PATENT OFFICE.

ARTHUR DOBSON, OF HALIFAX, ENGLAND, ASSIGNOR OF ONE-HALF TO THE FIRM OF DRAKES LIMITED, OF OVENDEN, HALIFAX, ENGLAND.

RETORT-DISCHARGING APPARATUS.

1,121,551.

Specification of Letters Patent. Patented Dec. 15, 1914.

Application filed February 17, 1914. Serial No. 819,208.

To all whom it may concern:

Be it known that I, ARTHUR DOBSON, a subject of the King of Great Britain, and resident of 58 Savile Park road, Halifax, in the county of Lancaster, England, have invented a certain new and useful Improvement in Retort-Discharging Apparatus, of which the following description, together with the accompanying sheets of drawings, 10 is a specification.

My invention relates to mechanism for performing the operation of discharging or effecting the withdrawal of the spent contents of retorts of the vertical or inclined 15 type used in the manufacture of gas, the distillation of shale, or for like purposes, and the object of my present invention is the production of said mechanism of such a character as will enable the withdrawal, or 20 discharging of any desired and suitable quantity of the spent material, (such as coke when coal gas is being manufactured) without the possibility of any larger quantity than is desired being at any time permitted 25 to descend by gravity or otherwise escape from the retort to which my apparatus is applied.

A further advantage secured by the employment of my mechanism in connection 30 with retorts for the manufacture of coal gas, is that the coke extracted is not broken or granulated to the extent that it is necessary for it to be to enable its discharge to be carried out by devices at present in use.

35 In the accompanying sheets of drawings which are illustrative of my invention:—Figure 1 is a longitudinal sectional elevation of apparatus produced in accordance with my invention. Fig. 2 is a cross sectional elevation of certain parts shown by Fig. 1. Figs. 3 and 4 are similar views to Fig. 2 (drawn to a reduced scale) but show certain of the parts in altered positions as hereinafter described. Fig. 5 is a perspective view showing two semi-cylindrical drums with one of the end walls of each cut away so as to show their formation as hereinafter described. Figs. 6 and 7 show the two drums referred to in detail. Figs. 8 and 40 9 are sectional end elevations of the semi-cylindrical drums hereinafter described, and illustrate modified forms of their cutting edges. Figs. 10 and 11 are front elevations of the drums shown by Figs. 8 and 9 and 45 55 illustrate the cutting edges approaching each

other and with alternative forms or shapes of said cutting edges.

A indicates the framework in which the parts are mounted said framework being arranged to be secured to the lower or discharge orifice B of a retort.

To attain the object of my invention I make use of mechanism, in connection with each retort, consisting of a pair of semi-cylindrical drums or longitudinal segments 65 of hollow cylinders 2 and 3 which for convenience I call drums, each having an opening in its periphery at one side. I arrange said drums so that their axes are co-incident, one drum 3 being so much less in diameter 70 and length than the other drum 2 that it will take into and operate within the latter, so that the drum 2 may be freely rotated in one direction, while the drum 3 is rotated in the other direction. The pivotal shafts 4, 75 4^a of the inner drum 3 are made to take through the hollow pivotal shafts 5, 5^a respectively of the outer drum 2 so that by any suitable gearing such as the spur wheel 6 (which may receive its motion by gearing 80 with a spur wheel carried by any prime or other motor shaft) motion may be transmitted to the outer drum 2, and by the bevel gear 7 mounted on the other hollow shaft 5 said drum may transmit motion through the 85 bevel gear 7^a and the bevel gear 7^b, which is fixed upon the shaft 4, to the drum 3, thus while one drum 2 is rotating in one direction the other drum 3 will rotate in the opposite direction.

In the walls of the framework A bearings 8 and 8^a are mounted to support the shafts of the drums 2 and 3, while on the upper parts of said walls A the projecting flange 9 is formed to overhang the outer edges of 95 the drums 2 and 3 in order to protect same from contact with the contents of the cavity above.

Although I have shown spur and bevel gearing as the means for transmitting motion to the drums 2 and 3, I am aware that ratchet wheel and pawl mechanism, rack and pinion devices or worm and worm wheel mechanism may be made use of for transmitting motion to said drums 2 and 3.

As these pairs of drums are being rotated they will at one time present their open sides to the base of the retort B, as shown by Figs. 1 and 2, so that the material within said retort B will, by gravity, descend and 100 105 110

enter the drum 3. By continuing the motions of the drums 2 and 3 from the position shown by Figs 1 and 2 the opposite or opposing edges 2^b and 3^b of the openings in these drums will commence to approach each other gradually cutting their way through the material which extends from the interior of the drums 2 and 3 up into the retort above. By these rotary motions being continued after said edges have met, as shown by Fig. 3, the portion or part of the material within is cut off or detached from that above and by the drums 2 and 3 still moving forward their open sides are gradually brought face downward as shown by Fig. 4 to deposit their contents into the space below. By constructing the drums 2 and 3 as above described, although they present a large opening for the entrance and exit into and out of them for the material which they have to deal with, yet at all times they entirely close the opening or passage leading to the base of the retort B. To enable these drums 2 and 3 to cut away or detach the quantity or portion of coke or the like that has descended into them, I provide the edges of their openings with teeth or prongs α so shaped as to enable them to dig or cut into the substances that have to be removed by them. In order that these cutting edges may be made to perform their functions by shearing actions, I preferably form them at an angle to the axis of their respective drums as illustrated by Figs. 1, 5, 6 and 7, so that on rotating in opposite directions the prongs or cutting edges at α^1 and α^2 will first approach each other, and by continuing in motion gradually shear away the material extending between them. Instead of the cutting edges being of the inclined form above described, I may have them parallel with the central line about which they rotate, and then form the prongs α of varying lengths, the longer prongs being made to extend beyond the edges of the drums but having their inner surfaces flat so that the distance between the points $d-d$ (Fig. 8) of the prongs on opposite sides of the drum exactly equals or is larger than the inner diameter of the drum. The longest prongs α^1 may be about midway the length of the two drums as shown by Fig. 10, the remaining prongs gradually diminishing in length toward the right and left where the shorter prongs α^2 are situated, or said longest prongs α^1 may be at one end of the drums 2 and 3 as shown by Fig. 11, the

remaining prongs gradually diminishing in length toward the other end of said drums 2 and 3. Or again, the longest prongs may be situated at each end and the remainder may gradually diminish in length toward the middle of said drums. In cases where it is thought advisable prongs on the other edges of the two drums may be made use of, so that when those in use become damaged a reversal in the direction of rotation of the drums 2 and 3 will throw the former set of prongs out of use, and bring the latter set into use. 70

Such being the nature and object of my said invention what I claim is:—

1. In retort discharging apparatus semi-cylindrical drums mounted so that they will rotate about a common axis independently 75 of each other, and means for transmitting motion to said drums.

2. In retort discharging apparatus, two drums one mounted to rotate within the other, supports upon which said drums are 80 mounted and driving gear for transmitting motion to said drums so as to rotate them in opposite directions.

3. In retort discharging apparatus, drums having their cutting edges formed at an 85 angle to their axes the cutting edge of one drum being at one angle and the other at another and opposite angle so that they may have a shearing effect when approaching each other, and means for transmitting motion to said drums. 90

4. In retort discharging apparatus, drums mounted to rotate upon a common axis, and each having an opening, and prongs or projections formed on the longitudinal edges 95 of said openings said prongs being of varying length and having their inner surfaces shaped so as not to interfere with the size of opening leading from their respective drums, substantially as described. 100

5. In retort discharging apparatus, drums mounted to rotate upon a common axis, and each having an opening, and prongs or projections formed on the longitudinal edges of said openings, said prongs being of varying length, substantially as described. 105

In testimony whereof I have signed my name to this specification in the presence of two subscribing witnesses.

ARTHUR DOBSON.
